[57] CLAIM

The ornamental design for a glass milk bottle, as shown and described.

DESCRIPTION

FIG. 1 is a front elevational view of a glass milk bottle showing my new design, the rear elevational view is the same;

FIG. 2 is a side elevational view taken from the left, the opposite side being the same;

FIG. 3 is a bottom plan view;

FIG. 4 is a top plan view;

FIG. 5 is a sectional view taken along the line 5—5 in FIG. 1;

FIG. 6 is a front elevational view of a modified form of the glass milk bottle, the rear elevational view is the same;

FIG. 7 is a side elevation of FIG. 6, the opposite side elevation is the same;

FIG. 8 is a bottom plan view of FIG. 6;

FIG. 9 is a top plan view of FIG. 6;

FIG. 10 is a cross sectional view taken on line 10—10 in FIG. 6;

FIG. 11 is a fragmentary sectional view taken on line 11—11 in FIG. 6;

FIG. 12 is a cross sectional view of the first embodiment of the glass milk bottle taken on line 12—12 in FIG. 1; and, FIG. 13 is a cross sectional view of the second embodiment of the glass milk bottle taken on line 13—13 in FIG. 6.
